A. T. DAWSON AND G. T. BUCKHAM.
ORDNANCE BREECH MECHANISM.
APPLICATION FILED OCT. 26, 1921.

1,422,037.

Patented July 4, 1922.

UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS LIMITED, OF WESTMINSTER, LONDON, ENGLAND.

ORDNANCE BREECH MECHANISM.

1,422,037.

Specification of Letters Patent. Patented July 4, 1922.

Application filed October 26, 1921. Serial No. 510,656.

To all whom it may concern:

Be it known that we, Sir ARTHUR TREVOR DAWSON, bart., and Sir GEORGE THOMAS BUCKHAM, knight, both subjects of the King of Great Britain, residing at Vickers House, Broadway, Westminster, in the county of London, England, have invented certain new and useful Improvements in or Relating to Ordnance Breech Mechanism, of which

10 the following is a specification.

This invention relates to ordnance breech mechanism of the kind comprising two cranks mounted in the breech screw carrier and driven through bevel gearing from the 15 axis pin or hinge bolt of the carrier, one of these cranks serving to unlock the breech screw and the other serving to withdraw the breech screw rearwardly in the carrier before being swung clear of the breech opening by the movement of the carrier about its 20 axis pin or hinge bolt; the chief object of the invention is to improve the breech mechanism disclosed in the specification of our prior British Patent No. 7189 of 1914.

25 According to the present invention the breech screw withdrawing crank, instead of engaging with the side of the breech screw as is the case in our previous breech mechanism referred to above, engages with the 30 lower part of the breech screw preferably at a point more or less immediately beneath the centre line of the breech screw and for this purpose may be carried at or near the inner end of a transverse horizontal shaft 35 the outer end of which carries a bevel pinion meshing with a bevel pinion on the carrier axis pin. The breech screw unlocking crank is arranged below a horizontal plane containing the axis of the gun and engages in

40 a slot formed in a lug which when the breech screw is in the locked position, extends downwardly at an angle to the said horizontal plane. The bevel pinion of the withdrawing crank meshes with a bevel 45 pinion appertaining to the unlocking crank so that the latter is operated from the carrier axis pin through the bevel pinion of the withdrawing crank.

In order that the said invention may be 50 clearly understood and readily carried into effect the same will now be described more fully with reference to the accompanying drawings, in which:—

55 Figures 1 and 2 are respectively a rear elevation and a side elevation illustrating

breech mechanism constructed in accordance with our invention, the mechanism being shewn closed and locked in these figures.

Figures 1^a and 2^a are diagrammatic views shewing the manner in which the unlocking 60 crank and the withdrawing crank operate, and

Figures 3, 4 and 5 are respectively a sectional rear elevation, a sectional side elevation and a sectional plan shewing clearly 65 the manner in which the unlocking crank and the withdrawing crank are driven.

A is the breech end of the gun, B the breech screw, C the carrier and C^x the carrier axis pin or hinge bolt. D is the unlocking crank which forms an integral part of a bevel pinion D' (see Figure 2). E is the withdrawing crank and e is the transverse horizontal shaft the inner end of which carries the said withdrawing crank and the 70 outer end of which carries a bevel pinion E' meshing with a bevel pinion C' on the carrier axis pin C^x and also meshing with the bevel pinion D' appertaining to the unlocking crank D. The withdrawing crank is 75 thus operated through the bevel pinions C', E' and the unlocking crank is operated through the bevel pinions C', E' and D'.

The withdrawing crank E has a roller E^x adapted to engage in a slot B^x in the lower 85 part of the breech screw B and the unlocking crank D has a roller D^x engaging in a slot F^x in a lug F' on a ring F in which the breech screw is slidably mounted as is well understood. The said unlocking crank is 90 arranged below a horizontal plane containing the axis of the gun and the lug F', when the breech screw is in the locked position, extends downwardly at an angle to the said horizontal plane.

95 In the locked condition of the breech mechanism, the cranks D, E and their associated parts occupy the position shewn (see particularly Figures 1^a and 2^a) with the roller D^x of the unlocking crank engaging in the 100 slot F^x and the roller E^x of the withdrawing crank E out of engagement with the slot E^x. During the operation of the mechanism to open the breech, the cranks move in the direction of the arrows in Figures 1^a and 2^a; 105 the breech screw is first unlocked by the crank D (during which time the crank E is performing an idle movement) and the crank E then engages in the slot B^x to move the breech screw rearwards in the carrier C 110

during which time the crank D is performing an idle movement. When the breech screw is fully withdrawn the carrier is swung into the open position by any suitable means. During the closing of the breech the reverse operations take place.

By reason of our improvements we obtain increased steadiness during withdrawal of the breech screw and a decreased distance 10 between the carrier axis pin and the centre line of the gun as compared with other breech mechanisms of this type.

What we claim and desire to secure by Letters Patent of the United States is:—

15 1. In ordnance breech mechanism, the combination with the breech screw, the swinging carrier in which said breech screw is mounted, and the axis pin of said carrier, of a breech screw withdrawing crank arranged to engage with the breech screw at a point substantially beneath the center line of the breech screw, a breech screw unlocking crank arranged with its axis in substantially the same horizontal plane as the 25 axis of the withdrawing crank and means for operating said cranks from the carrier axis pin.

2. In ordnance breech mechanism, the combination with the breech screw, the 30 swinging carrier in which said breech screw is mounted, and the axis pin of said carrier, of a breech screw unlocking crank whose axis is arranged a substantial distance below a horizontal plane containing the axis 35 of the gun, a member having a slot with which said crank is adapted to engage, said slot, when the breech screw is in the locked position, extending downwardly at an angle to the said horizontal plane, a breech screw 40 withdrawing crank, and means for operating said cranks from the carrier axis pin.

3. In ordnance breech mechanism, the combination with the breech screw the swinging carrier in which said breech screw 45 is mounted and the axis pin of said carrier, of a breech screw unlocking crank whose axis is arranged a substantial distance below a horizontal plane containing the axis of the gun, a member having a slot with 50 which said crank is adapted to engage, said slot, when the breech screw is in the locked position, extending downwardly at an angle to the said horizontal plane, a breech screw 55 withdrawing crank and bevel gearing for operating said cranks from the carrier axis pin.

4. In ordnance breech mechanism, the combination with the breech screw, the swinging carrier in which said breech screw 60 is mounted and the axis pin of said carrier, of a breech screw unlocking crank arranged below a horizontal plane containing the axis of the gun, a member having a slot with 65 which said crank is adapted to engage, said slot, when the breech screw is in the locked

position, extending downwardly at an angle to the said horizontal plane, a breech screw withdrawing crank arranged to engage with the breech screw at a point substantially beneath the centre line of the breech screw 70 and means for operating said cranks from the carrier axis pin.

5. In ordnance breech mechanism, the combination with the breech screw, the swinging carrier in which said breech screw 75 is mounted and the axis pin of said carrier, of a breech screw unlocking crank arranged below a horizontal plane containing the axis of the gun, a member having a slot with which said crank is adapted to engage, said slot, when the breech screw is in the locked position, extending downwardly at an angle to the said horizontal plane, a breech screw withdrawing crank arranged to engage with the breech screw at a point substantially beneath the centre line of the breech screw 80 and bevel gearing for operating said cranks from the carrier axis pin.

6. In ordnance breech mechanism, the combination with the breech screw, the 90 swinging carrier in which said breech screw is mounted and the axis pin of said carrier, of a breech screw unlocking crank, a breech screw withdrawing crank, means for operating the withdrawing crank from the carrier axis pin, and means for operating the 95 unlocking crank from the withdrawing crank.

7. In ordnance breech mechanism, the combination with the breech screw, the 100 swinging carrier in which said breech screw is mounted and the axis pin of said carrier, of a breech screw unlocking crank, a breech screw withdrawing crank, a bevel pinion connected to said withdrawing crank, a bevel 105 pinion on the carrier axis pin meshing with the first-mentioned pinion, and a bevel pinion connected to said unlocking crank, the last mentioned pinion meshing with the pinion of the withdrawing crank.

8. In ordnance breech mechanism, the combination with the breech screw, the swinging carrier in which said breech screw is mounted and the axis pin of said carrier, of a breech screw unlocking crank arranged 110 below a horizontal plane containing the axis of the gun, a member having a slot with which said crank is adapted to engage, said slot, when the breech screw is in the locked position, extending downwardly at an angle 115 to the said horizontal plane, a breech screw withdrawing crank arranged to engage with the breech screw at a point substantially beneath the centre line of the breech screw, means for operating the withdrawing crank 120 from the carrier axis pin, and means for operating the unlocking crank from the withdrawing crank.

9. In ordnance breech mechanism, the combination with the breech screw, the 125

swinging carrier in which said breech screw is mounted and the axis pin of said carrier, of a breech screw unlocking crank arranged below a horizontal plane containing the axis 5 of the gun, a member having a slot with which said crank is adapted to engage, said slot, when the breech screw is in the locked position, extending downwardly at an angle to the said horizontal plane, a breech screw 10 withdrawing crank arranged to engage with

the breech screw at a point substantially beneath the centre line of the breech screw, a bevel pinion connected to said withdrawing crank, a bevel pinion on the carrier axis pin meshing with the first-mentioned pinion and 15 a bevel pinion connected to said unlocking crank, the last mentioned pinion meshing with the pinion of the withdrawing crank.

ARTHUR TREVOR DAWSON.
GEORGE THOMAS BUCKHAM.
